Spur Padden

Inventor.

John M. Hagerty

UNITED STATES PATENT OFFICE.

JOHN M. HAGERTY, OF FARMINGTON, WEST VIRGINIA.

CAR-COUPING.

SPECIFICATION forming part of Letters Patent No. 439,242, dated October 28, 1890.

Application filed February 7, 1890. Serial No. 339,620. (No model.)

To all whom it may concern:

Be it known that I, JOHN M. HAGERTY, a citizen of the United States, residing at Farmington, in the county of Marion and State of West Virginia, have invented a new and useful Car-Coupler, (which has not been patented in any country,) of which the following is a specification.

My invention relates to improvements in car-couplers; and the object of my improvement is to obtain a self-coupler on simple principles and having strength and durability. I attain these objects by a draw-head coupling bar and roller, as illustrated in the accompanying drawings, in which—

Figure 1 is a coupler complete, excepting coupling-bar. Fig. 2 is the roller; Fig. 3, the coupling-bar, and Fig. 4 inner side view when coupled.

Draw-head *a* contains recess *b* for receiving coupling-bar *e*.

Draw-head *a* has an obtuse angle-shaped aperture *c* horizontally through draw-head, in which is placed roller *d*, which, from the shape of aperture *c*, can be shoved back and up.

Coupling-bar *e* is made with enlarged ends *g g*. When coupling-bar *e* is placed in recess *b*, it is held in a horizontal position by roller *d* and draw-head *a*, so as to enter recess *b* in opposite draw-head *a* unaided. Back walls *j j* form back-stay for coupling-bar *e*. When coupling-bar *e* enters recess *b*, it shoves roller *d* back, then up, so that enlarged end *g* passes under roller *d*. Roller *d* then drops down and forward, aided by slant *f*; bottom of aperture *c*, and thus prevents coupling-bar *e* from leaving recess *b* until roller *d* is displaced, which is done by chains *i i*, attached to each end of roller *d* and to rod *h h*, the top *k* over back

part of recess *b* holds coupling-bar *e* in horizontal position when roller *d* is displaced.

Draw-head *a* is made with aperture *n*, in which a pin may be used when coupling to an ordinary link-and-pin draw-head.

Draw-head *a* is made with aperture *t*, in which draw-bar *r* is secured. Aperture *t* may be made oblong, so that draw-head *a* can be placed high or low on cars of different heights, so that all draw-heads can be placed on same level. Draw-head *a* may also be made for double draw-bars *o o*, which is secured by bar through aperture *p*.

Coupling-bar *e* may be made hollow, as indicated by dotted lines *q q*, so that it can be used in coupling to an ordinary draw-head with pin.

l l l are washers, and *m* a key.

All the above are substantially as illustrated in the accompanying drawings.

What I claim as my invention, and desire to secure by Letters Patent, is—

1. A draw-head provided with the series of slots *p p p* and the oblong recess *t*, for the purpose of elevating and lowering the same, substantially as described.

2. The wedge-catch consisting of the combination of draw-head *a*, roller *d*, and coupling-bar *e*, with angled shoulders *g*, substantially as described.

3. The combination of the draw-head provided with the obtuse-angled guide-slots *c*, the roller *d*, and the coupling-bar *e*, all substantially as described.

JOHN M. HAGERTY.
